UNITED STATES PATENT OFFICE.

MAGNUS LARSEN, OF ARMSTRONG, IOWA.

WAGON-DUMP.

1,333,429.

Specification of Letters Patent. Patented Mar. 9, 1920.

Application filed October 23, 1918. Serial No. 259,375.

To all whom it may concern:

Be it known that I, MAGNUS LARSEN, a citizen of the United States, residing at Armstrong, in the county of Emmet and State of Iowa, have invented new and useful Improvements in Wagon-Dumps, of which the following is a specification.

The object of the invention is to provide an automatic wagon dump particularly designed for the unloading of grain from wagons. To this end the invention comprises a platform in which is swingingly mounted a frame designed to receive the wheels of a wagon. This frame is mounted so that it may be oscillated to lower one end of the wagon, thereby depositing the contents thereof. The frame is secured firmly in position except at such times as it is desired to dump the wagon and there is associated with the operating mechanism of the frame, a means for automatically returning the frame to normal position after the wagon has once been dumped.

Other and further objects appear in the following description wherein the invention is set forth in detail.

To the exact construction in which it is shown and described, the invention is not to be restricted. The right is reserved to make such changes or alterations as the actual reduction to practice may suggest, in so far as such changes or alterations are compatible in spirit with the annexed claims.

The same numerals of reference designate the same parts throughout the several figures of the drawings, wherein:

Figure 1 is a view in side elevation showing the practical application of the invention.

Fig. 2 is a top plan view.

Fig. 3 is a section on the line 3-3 of Fig. 2.

Fig. 4 is a section on the line 4-4 of Fig. 2.

Fig. 5 is a section on the line 5-5 of Fig. 2.

Fig. 6 is a section on the line 6-6 of Fig. 2.

Fig. 7 is a vertical sectional detailed view illustrating the operative connection between the wheel and the drum.

Fig. 8 is a section on the line 8-8 of Fig. 7.

Referring to the drawings, there is shown a platform 1 elevated from the ground level and reached by means of an inclined way or

entrance platform 2. The platform 1 is formed with the longitudinal slots 3 spaced apart in parallel relation with each other a distance equal to the usual gage of running gear. The two longitudinal slots 3 are connected by means of a transverse slot 4 at one end. A U-shaped frame 5 lies in the slots 3 and 4, the legs of the U lying in the former slots and the transverse member in the latter slot. This frame 5 is pivotally mounted and when lying in a horizontal plane its upper face is flush with the top face of the platform 1. It is pivotally mounted substantially at the center of its length and to this end the legs of the frame on the under surface are provided with laterally projecting pivot studs 6 which loosely engage in bearing members 7 secured to the under side or surface of the platform. A stop 8 is mounted on the under side of the platform 1 and the transverse portion of the frame 5 strikes this slot to preclude the passing downwardly of this portion of the frame through the slot. Thus while the frame is mounted for oscillating movement, this oscillating movement may take place only on one side of the pivot point on which it is mounted.

The platform 1 at that end of the frame 5 remote from the transverse member is formed with an opening which is closed by a removable trap door 9. This is for the purpose of permitting teams to enter the platform and dumping the contents of their wagons after the same have passed upon the frame 5, the contents, of course, being deposited not on top of but below the platform 1.

It is intended that the platform 11 shall be built adjacent to a side wall, but if it is not convenient to thus position the platform, it may be built at a point away from any wall but in such a case should be provided with a side wall 10 which may be attached to the platform in any acceptable manner. On this side wall 10 there is mounted a bracket 11, the latter having an outboard bearing support 12 in which there is journaled one end of a shaft 13, the latter having at the other end a suitable bearing mounted in the wall 10. On this shaft 13, between the outboard bearing support 12 and the wall 10 there is carried a wheel 14 the periphery of which is frictionally engaged by a brake lever 15 pivotally mounted at one end in a supporting bracket 16 car-

ried by the bracket 11. The remaining end of this lever 15 is formed with a handle for the convenience of hand manipulation and the lever may be engaged with or disengaged from a latch member 17 carried on the wall 10. A spring 18 attached at one end to the lever 15 and the other end to the bracket 11 tends normally to keep the brake lever away from the wheel 14.

10 The wheel 14 serves the purpose of a brake element and to that end is fixedly attached to the shaft 13 but besides this brake wheel the shaft 13 carries a drum 19 which is loosely mounted on the shaft but precluded from longitudinal movement thereon. On that end facing the wheel 14, the drum is formed with a plurality of inset ratchet teeth 20 and these are engaged by a spring held pawl 21 carried by the wheel 14. This 20 construction provides for a relative angular movement between the drum and the wheel when the drum is turned in one direction but precludes such angular movement when the drum is turned in the opposite direction.

15 Encircling the drum there is a cable 22 one end of which connects with the eye 23 carried by the transverse member of the frame 5. In passing from the frame to this eye the cable is trained over the pulley 24 attached beneath the platform 1 and is further trained over a pulley 25 mounted on the under face of the platform directly below the eye 23. In order that the cable may pass from below the platform to the drum 30 an opening or hole 26 is formed in the platform 1. To the remaining end of the cable 22 there is attached a counter-weight 27 and the cable is fixedly secured to the drum at substantially an intermediate point between the counter-weight and its point of 35 attachment with the eye 23.

40 It is obvious from this construction that as the drum turns in one direction that end of the cable carrying the weight un-45 winds therefrom and that end attached to the frame 5 is wound thereupon. The re-50 verse turning movement of the drum un-winds that part of the cable connected to the frame but winds up that part connected to the counter-weight. Thus if the frame is in 55 a position where the transverse portion is raised above the platform 1, the counter-weight will be elevated because its portion of the cable will be wound on the drum and the remaining portion of the cable un-wound therefrom. But the counter-weight is provided for the purpose of keeping the frame normally in its lower position. Therefore, if there is nothing to retain the frame 60 elevated, the counter-weight will act to rotate the drum with the result that the portion of the cable connected with the frame will be wound on the drum and the frame thereby pulled down into normal position. 65 The pawl 21 is so positioned that such a

movement of the drum will be permitted when the wheel 14 is held stationary. Thus if the frame 5 has been elevated and the drum retained in locked position by the brake lever 15, the counterweight may operate to automatically wind up the slack in the cable if the force tending to keep the frame elevated is removed and the frame is allowed to drop.

70 In the operation of the invention, it is the purpose to drive laden teams up the entrance platform so that the wagon wheels may be made to rest on the frame 5. The trap door 9 is then raised but the frame is precluded from moving because the brake lever is engaged by the latch member 17 and the wheel 14 is thus prevented from moving and hence the platform may not move because the pawl 21 engages the teeth 20 to prevent angular movement of the drum 80 in the direction in which it would have to move if the frame were raised by any force applied to that portion of the cable attached to it. Thus the wagon having been positioned on the frame 5, the operator charged 85 with the care of dumping the wagon, may release the lever 15 from the catch and relieve its pressure on the wheel 14 sufficiently to permit the weight of the wagon to rock the frame 5 in a direction which 90 will move its rear end downwardly. When the desired angle has been reached, the contents of the wagon may be deposited through an opening normally closed by the trap door 9. The wagon having thus been dumped, 95 the team may be driven off the platform 1 in the opposite direction from which it entered the same, an inclined platform similar to the entrance platform 2 being provided to permit the team to leave the platform 1. 100 This latter platform, however, is not shown in the present drawings and is not essential to an understanding of the invention. 105

As the wagon is drawn off the frame 5, the latter is, of course, moved down to its 110 normal position, at which time the counter-weight operates to take up the slack on the cable 22 preparatory to the frame's receiving another wagon for dumping.

Having described the invention what is 115 claimed as new and useful is:

1. In a device of the character described, the combination with a platform, of a U-shaped frame inset in the platform with its top face lying flush with the top face of the 120 platform, means for pivotally mounting the frame in said platform so that it may be permitted rocking movement in but one direction, a supporting bracket mounted adjacent said platform, a shaft rotatably 125 mounted in said supporting bracket, a wheel carried by said shaft, a brake lever engageable with the periphery of said wheel, a drum mounted on said shaft for relative angular movement in but one direction only, 130

a cable encircling said drum and having one end connected with said frame, and a counter-weight carried at the remaining end of the cable for the useful purpose specified.

- 5 2. In a device of the character described, the combination with a platform, of a U-shaped frame inset in the platform with its top face lying flush with the top face of the platform, means for pivotally mounting the frame in said platform so that it may be permitted rocking movement in but one direction, a supporting bracket mounted adjacent said platform, a shaft rotatably mounted in said supporting bracket, a wheel

carried by said shaft, a brake lever engageable with the periphery of said wheel, a drum loosely mounted on said shaft adjacent the said wheel, the drum being provided with a plurality of inset ratchet teeth on that end facing the wheel, a spring held pawl carried by the wheel and engaging said ratchet teeth, a cable encircling the drum and having one end connected to the said frame, and a counter-weight carried at the remaining end of the cable for the useful purpose specified.

In testimony whereof I affix my signature.
MAGNUS LARSEN.
